ATTORNEY

UNITED STATES PATENT OFFICE.

RICHARD EARL NEELY, OF TERRE HAUTE, INDIANA.

RAIL CLAMP.

Application filed December 23, 1922. Serial No. 608,753.

To all whom it may concern:

Be it known that I, RICHARD EARL NEELY, a citizen of the United States, residing at Terre Haute, in the county of Vigo and 5 State of Indiana, have invented new and useful Improvements in Rail Clamps, of which the following is a specification.

This invention relates to improvements in clamps especially adapted for securing trolley wire insulators to the supporting beams in mines, an object being to provide a clamp which may be quickly and easily applied to 10 an ordinary overhead railroad rail or I-beam, (as commonly used in mine tunnels) 15 whereby an insulator may be attached for the support of a trolley wire.

With the above and other objects in view, the invention further includes the following novel features and details of construction, 20 to be hereinafter more fully described, illustrated in the accompanying drawings and pointed out in the appended claim.

In the drawings:—

Figure 1 is a transverse section through 25 a rail with the invention attached.

Figure 2 is a fragmentary view at right angles to Figure 1.

Figure 3 is a detail perspective view of 30 one member of the clamp.

Figure 4 is a similar view of the other member.

Referring in detail to the drawings, wherein like characters of reference denote corresponding parts, the clamp is shown as comprising a pair of relatively adjustable members 10 and 11, each of which includes a head 12, while extending from this head are upwardly and inwardly inclined lips 13. The heads 12 together with the lips 13 provide notches 14 for the reception of the flanges of the rail or I-beam, the former being illustrated and indicated at 15. The lips are adapted to overlie the opposite side edges of the flange 16 of the rail, so that 45 when the members 10 and 11 are secured together in a manner to be hereinafter explained, the lips 13 will tightly grip the flange of the rail.

Extending inwardly from each of the

heads 13 is a bar 17, the bar of the member 11 being offset with respect to the bar of the member 12 and providing a space for the reception of the last mentioned bar. Extending downwardly from the inner end of the bar 17 of the member 11 is a lug 18, while a similar lug 19 extends down from and forms a part of the head 12 of the member 10. The lugs 18 and 19 are provided with openings and the opening in the former lug is threaded for engagement with the inner end 50 of an adjusting bolt 20, whose head bears against the outer face of the lug 19.

Extending downwardly from the member 11 is a threaded lug 21, with which a suitable insulator is adapted to threadedly engage, so that when the clamp is secured to the support which is herein shown as the rail 15, the insulator will serve as a support 55 for a trolley wire.

It is preferred to provide insulation 22 and 23 between the rail 15 and the members 10 and 11 of the clamp, so that if desired, a wire engaging member other than an insulator may be attached to the lug 21.

The invention is susceptible of various 70 changes in its form, proportions and minor details of construction and the right is herein reserved to make such changes as properly fall within the scope of the appended claim.

Having described the invention what is 75 claimed is:—

A clamp of the class described comprising a pair of relatively movable members, each of said members including a head, a bar also 80 extending from said head, the bars of one head being offset with respect to the bars of the other heads, with the bars arranged in overlapping relation, means carried by one of said members for attachment to an insulator, a lug carried by each member and provided with an opening and a bolt extending from the openings, whereby the members may be relatively adjusted and held in adjusted position.

In testimony whereof I affix my signature.

RICHARD EARL NEELY.
